UNITED STATES PATENT OFFICE

160,327

WHEEL SPINNER

Kenneth Lowe, East Alton, Ill.

Application April 3, 1950, Serial No. 8,945

Term of patent 7 years

(Cl. D14—3)

To all whom it may concern:

Be it known that I, Kenneth Lowe, a citizen of the United States, residing at East Alton, in the county of Madison and State of Illinois, have invented a new, original, and ornamental Design for a Wheel Spinner, of which the following is a specification, reference being had to the accompanying drawing, forming part thereof.

Figure 1 is a perspective view of a wheel spinner, showing my new design;

Figure 2 is another perspective view thereof, taken from a side opposite to that shown in Figure 1; and

Figure 3 is a top plan view of the same.

I claim:

The ornamental design for a wheel spinner, as shown.

KENNETH LOWE.
